UNITED STATES PATENT OFFICE.

WILLIAM N. BOOTH AND ISAAC LEWIS, OF CLEVELAND, OHIO.

DESIGN FOR A CRANK-SHAFT.

SPECIFICATION forming part of Design No. 25,717, dated June 30, 1896.

Application filed February 18, 1896. Serial No. 579,798. Term of patent 31 years.

To all whom it may concern:

Be it known that we, WILLIAM N. BOOTH and ISAAC LEWIS, citizens of the United States, residing at Cleveland, in the county of Cuyahoga, State of Ohio, have invented and produced a new and original Design for a Crank-Shaft, of which the following is a specification, reference being had to the accompanying drawings, showing the same.

Figure 1 is a side elevation, full size, of one end of a crank-shaft embodying our design. Fig. 2 is an end view of the same. Fig. 3 is a view of the complete article somewhat reduced.

The essential feature of our design consists in the peculiar conformation of the periphery of a crank-shaft. Our design is embodied in that portion of the shaft where the crank is attached, and comprises a curved portion and two plane surfaces, the plane surfaces being adjacent and the three surfaces forming conjointly the circumference of this part of the crank-shaft.

In the accompanying drawings, 2 represents one end of a crank-shaft, which is circular in cross-section in part and in part formed with two adjacent plane-surface portions and an interconnecting curved-surface portion. The

extremity 3 of said shaft is of the same diameter as the shaft proper, and its periphery comprises a curved portion 4, which is concentric with the longitudinal axis of the shaft proper. The remainder of the periphery includes two plane surfaces 5 6. These two surfaces represent adjacent faces of a frustum of a pyramid, the base of the pyramid being at the meeting-point of the portion 3 with the circular end portion 2 of the crank-shaft. Furthermore it will be seen that the curved-surface portion 4 is parallel with the longitudinal axis of the shaft proper, or the same distance from said axis at all points, while the plane-surface portions 5 6 are inclined toward the axis, converging in the direction of the ends of the crank-shaft. A central cylindrical boss 7 with screw-threads circumferentially terminates the ends of the crank-shaft.

What we claim is—

The design for a crank-shaft as herein shown and described.

WILLIAM N. BOOTH.
ISAAC LEWIS.
